J. F. SALES.
MACHINE FOR CUTTING SEED POTATOES.
APPLICATION FILED FEB. 9, 1921.

Patented Mar. 28, 1922.

UNITED STATES PATENT OFFICE.

JOHN F. SALES, OF OUTLOOK, WASHINGTON.

MACHINE FOR CUTTING SEED POTATOES.

1,410,838.

Specification of Letters Patent. Patented Mar. 28, 1922.

Application filed February 9, 1921. Serial No. 443,568.

To all whom it may concern:

Be it known that JOHN F. SALES, a citizen of the United States, residing at Outlook, in the county of Yakima and State of Washington, has invented certain new and useful Improvements in Machines for Cutting Seed Potatoes, of which the following is a specification, reference being had therein to the accompanying drawings.

10 This invention relates to a machine for cutting seed potatoes, and has for its object the construction of a simple and efficient apparatus, whereby the operator can be seated and quickly cut seed potatoes, or cut the tops off of beets, or do like or similar work, throwing the potatoes, or beets, etc., into a sack supported upon the apparatus in an open position.

With this and other objects in view, my 20 invention comprises certain other combinations, constructions and novel arrangements, as will be hereinafter specifically described, illustrated in the accompanying drawings, and more particularly pointed out in the 25 appended claim.

In the drawing:

Figure 1 is a perspective view of an apparatus constructed in accordance with the present invention.

30 Figure 2 is a section, taken on line 2—2, Fig. 1.

Figure 3 is a section, taken on line 3—3, Fig. 1.

Referring to the drawings by numerals 1 35 comprises the frame to which is attached the primary standard 2 and the auxiliary standard 3.

Upon the upper end of the auxiliary standard 3 is placed a seat 4, which is secured to the 40 standard by means of braces 5, fastened by screws 6, upon the opposite sides of the standard 3. A block 7 is fastened against the standard 3, and a back 8 is secured to the block 7 and the seat 4. This back comprises 45 a vertical piece 9, to the upper end of which is attached the horizontal back piece 10.

Secured upon the upper end of the primary standard 2 is a platform 11. This platform 11 comprises the board 12 that is 50 protected on its upper face by a metal covering 13. A knife 14 is provided with a threaded bolt-like extension 15 that extends

through the metal covering 13 and the board 12 and into the nut 16, which nut is countersunk in the under face of the board 12, so 55 that when the platform is upon the standard 2, the knife is securely retained in place.

Angle braces 17 are fastened to the sides of the standard 2 and are also fastened to the under face of the board 12, thereby securely 60 retaining the platform upon the standard 2.

A primary horizontal bracket 18 is fastened to the outer face of standard 2 under the platform 11, and fastened to the opposite face of standard 2 is an auxiliary horizontal bracket 19. Slidably mounted upon the brackets 18 and 19 is a sack rack 20, which rack is substantially U-shaped and comprises side arms 20^a with an upwardly-bowed connection portion or grip 20^b; the arms 20^a 70 extend through suitable apertures formed in the primary and auxiliary brackets, and each arm, near its outer end, is provided with an outwardly-extending sharpened spur 21, over which is hooked a bag shown 75 by dotted lines 22. The outer ends of the primary bracket 18 is also formed into shape of horns or sharpened spurs 21^a, over which the bag 22 is hooked.

The operator sits upon the seat 4 and cuts 80 vegetables or fruits by means of the knife 14, and after cutting, the vegetables or fruits can be easily deposited or placed in the bag 22 that is retained in an open position upon the primary bracket 18 and the sack 85 rack 20.

While I have described the preferred embodiment of my invention and have illustrated the same in the accompanying drawing, in the extensive manufacture of my apparatus, certain minor changes or alterations may be found desirable and I, therefore, reserve the right to make such alterations or changes, as shall fairly fall within the scope of the appended claim. 95

What I claim is:

In an apparatus of the class described, the combination of a supporting board, a thin sheet metal covering on the top and side-edges of said board, a knife having its inner end resting upon said metal covering, 100 a bolt-like threaded extension on the knife and projecting through said metal covering and board, a nut countersunk in the under

face of said board and threaded upon said extension whereby the nut is held against rotation, thereby firmly holding said extension and binding the inner end of the knife 5 against said metal covering in a biting like engagement, for holding the covering and the knife in set positions, and a standard

against the inner face of the board and entirely covering the bolt-like threaded extension and nut, substantially as shown and 10 described.

In testimony whereof I hereunto affix my signature.

JOHN F. SALES.
